CLAIM

The ornamental design for a rocker attachment for a baby car seat, as shown and described.

DESCRIPTION

FIG. 1 is a top perspective view of the rocker attachment for a baby car seat showing my new design;
FIG. 2 is a left side elevational view thereof;
FIG. 3 is a bottom plan view thereof;
FIG. 4 is a front elevational thereof;
FIG. 5 is a rear elevational view thereof;
FIG. 6 is a top plan view thereof;
FIG. 7 is a right side elevational view thereof;
FIG. 8 is a top plan view thereof, with the flange expanded and rotated and the pull cord retracted;
FIG. 9 is a left side elevational view of the rocker attachment for a baby car seat in an operating condition; and,
FIG. 10 is another left side elevational view of the rocker attachment for a baby car seat in an operating condition.
